BALL FRAME FOR SHAKER CHUTES

Donald U. Rich, Teaneck, N. J., assignor to
American Car and Foundry Company, New
York, N. Y., a corporation of New Jersey

Application July 15, 1932. Serial No. 622,629

10 Claims. (Cl. 198—220)

This invention relates generally to reciprocating conveyors of the trough type usually employed in mines and for various other purposes and known in the art as shaker chutes.

5 The primary object of this invention is the provision of a new and improved ball frame for shaker chutes.

Reciprocating conveyors of the type involved are composed usually of a plurality of trough 10 sections suitably connected end to end to form a unit which is reciprocated by means of a suitable power driven device. At intervals these trough sections are supported for reciprocation in a desired manner by elements known in the art as ball frames. The present invention is directed 15 to such an element. During the reciprocation of these conveyors forces arise which act in an upward direction and tend to buckle the conveyor. Forces also arise which tend to shift the conveyor sidewise. In view of the tendency for buckling and sidewise shifting the present invention 20 contemplates a ball frame for a reciprocating conveyor which is so formed as to prevent excessive sidewise and vertical shifting of the conveyor but still provide a construction in which 25 reciprocation of the conveyor is readily effected.

A further object of this invention is the provision of a ball frame for reciprocating conveyors which is easy and inexpensive to manufacture 30 and strong and durable in operation.

Other objects and advantages of this invention will be apparent from the following description taken in conjunction with the accompanying drawings in which:

35 Figure 1 is a top plan view of one form of the invention.

Fig. 2 is a side elevation of the device shown in Fig. 1, the view having certain parts broken away to disclose other parts in section and also showing a portion of a trough section associated therewith.

40 Fig. 3 is an end view of the device shown in Fig. 1 showing a trough section in association therewith.

45 Fig. 4 is a fragmentary detail view, partly in section, showing a modification of the construction shown in Figs. 1, 2 and 3.

Fig. 5 is a fragmentary detail view, partly in 50 section, showing another modification of the construction shown in Figs. 1, 2 and 3.

Fig. 6 is a top plan view of another and modified form of the invention.

55 Fig. 7 is a side elevation of the construction shown in Fig. 6.

Fig. 8 is an end view of the construction shown in Fig. 6.

Fig. 9 is a top plan view of a modified form of body member.

Fig. 10 is an end view of the construction 60 shown in Fig. 9, and

Fig. 11 is a fragmentary detail view of a portion of the construction illustrated in Fig. 8.

Referring now more particularly to Figs. 1, 2 and 3, the ball frame of the present invention 65 comprises a base frame A and a reciprocable body member B with which a trough section C of a conveyor is connected in a manner such as more clearly described hereinafter.

The base frame A comprises a pair of spaced 70 supporting members 2, downwardly facing channels in the instance shown, connected by upwardly facing, parallel arranged channel members 4 which constitute guideways or track members for suitable anti-friction elements such as 75 the balls 6 which are adapted to roll in the members 4 and which support the body member B.

The body member B comprises a metal plate 8, I-shaped in plan in the instance shown, provided with a slot 10 to receive the depending 80 flange 12 (see Fig. 3) of a connector 14 secured to the under side of the trough section C. The connector 14 may be an angle or a T as desired, suitably connected to the trough section as by being riveted or welded thereto.

85 The side edges of the body member B are downwardly flanged as at 16 for stiffening purposes and portions 18 of said flanges are arranged between the parallel flanges or legs 20 of the members 4 to constitute end barriers for limiting movement of the balls 6 as well as to provide scraper members to force foreign matter such as coal dust or the like out of the channels 4 either at the ends thereof or through suitable openings 90 22 formed of the webs 24 of said channels.

95 The end edge portions of the body member B are downwardly and inwardly bent as by being flanged at 26 to form longitudinally extending guiding recesses 27 each of which receives a restraining flange 28 formed as an upwardly inclined extension of one of the flanges 20 of each of the guideways 4 whereby the body member is guided during reciprocation on the balls 6. The 100 interengagement of the guideways 4 and body member B at the recesses 27 also provides a construction in which extensive vertical and sidewise shifting of the body member relative to the frame is prevented.

105 The construction shown in Fig. 4 is quite similar to that disclosed in Figs. 1-3 inclusive but in 110

this instance the body member B has its end edges downwardly and then inwardly flanged as at 30 to lie parallel with the main portion of the body member B and parallel with a flange 32 which extends at substantially right angles to the upstanding flange 20 of the channel member 4. In the instance shown in Fig. 4 it is obvious that excessive vertical shifting of the body member B relative to the channel 4 is prevented by contact of the flange 30 with the flange 32 of channel member 4. Excessive sidewise shifting of the body member B relative to the channel 4 is, in Fig. 4, prevented by contact of the edge portion of the flange 32 with the vertical portion 34 of the depending flange of the end of the body member B.

In Fig. 5 the body member B has its end portions downwardly flanged as at 36 and then inwardly flanged at 38, the flange 38 underlying the outwardly extending flange 40 of a Z-section 42 secured to the channel 2 and constituting a portion of the track member for the ball 6, the remainder of the track portion being formed by an angle 44 spaced somewhat from the Z-section 42 to provide a space 46 through which foreign matter such as coal dust or the like may pass to prevent clogging of the guideway.

In Figs. 6, 7 and 8 there is disclosed an arrangement in which the body member, indicated generally at D, is mounted on a supporting or base frame comprising the channels 2 and a pair of parallel guideways or track members, the upper and lower members of which are separated by the anti-friction balls 6 interposed therebetween and the upper members of which guideways are connected to the body member D. The guideways comprise the spaced, oppositely arranged Z-sections 48, the upper flanges 50 of which incline upwardly as shown clearly in Fig. 8, and the upper members of the guideways comprise plates 52 to which the body member D is welded as at 54, the outer edge portions of said members 52 being downwardly and then inwardly flanged as at 56 to underlie the beforementioned flanges 50 of the angles 48. The inner edge portions of the members 50 are downwardly flanged as at 58 and obviously cooperate in the construction in such a manner as to provide inner walls for the guideways to retain the balls 6 against displacement. To furnish stiffness for the body member D the side edge portions thereof, intermediate the guideway members 50, are downwardly flanged as at 60 and the members 50 are so formed as to provide depending flanges 62 to serve as end barriers to retain the balls 6 in their guideways.

In the construction shown in Figs. 1 and 6 spacers 64 are secured in the guideways to retain the balls in spaced relation.

In the construction shown in Figs. 6-8 inclusive it is apparent that a space 66 is provided the full length of the upper members 50 of the guideways through which any foreign matter such as coal dust or the like may escape to prevent clogging of the guideways. The Z-sections 48 may be welded to the channels 2 but in the instance shown they are riveted as at 68 and the lower edge portion of the end barriers 62 are provided with arcuate recesses to clear the rivets during reciprocation of the body member.

Figs. 9 and 10 disclose a modified form of body member comprising a substantially rectangular plate 70 having its end edge portions downwardly and inwardly bent as at 72 and the end barriers in this instance comprise angle-shaped

clips 74 welded as at 76 to the plate 70 and arranged in such a position as to extend into the guideways. In this instance the plate 70 is also provided with a slot 78 to receive the depending portion of a connector secured to a trough section.

From the above description it is believed that the construction and operation of the ball frame of the present invention will be fully apparent to those skilled in the art. Referring to the construction shown in Figs. 1-3 inclusive, reciprocation of the trough section 14 will cause shifting of the body member B on the balls 6. Should there be a tendency for the body member B to shift vertically relative to the base frame, it is apparent that this is prevented by contact of the flanges 26 with the flanges 28 of the channel members 4. Tendency of sidewise shifting of the trough and body member is prevented by contact of the flanges 26 with the flanges 28.

In the construction shown in Figs. 6-8 inclusive, reciprocation of the body member of the ball frame takes place on the balls 6 in a manner similar to that described with relation to Figs. 1-3 inclusive. In Figs. 1-3 foreign matter 100 such as coal dust or the like is pushed from the ends of channels 4 by the flanges 18 and also is discharged from the channels 4 through the openings 22. In the construction shown in Fig. 5 the foreign matter is easily and quickly expelled from between the members 42 and 44 forming the guideway through the space 46 provided therebetween. In Figs. 6-8 inclusive, due to the space between the lower edge portions of the flanges 58 and the angles 48, it is apparent that the end barriers 62 can maintain the guideway clear of obstruction by forcing the coal dust or other foreign matter from the guideway.

The drawings herein illustrate several embodiments of the invention but it is to be understood that they are for illustrative purposes only and various changes in the form and proportions of the construction shown may be made within the scope of the appended claims without departing from the spirit of the invention.

What is claimed is:

1. In a ball frame for shaker chutes, spaced upper race members each having an inwardly facing longitudinal guiding recess, a body member connecting the upper race members, lower race members having portions projecting into said recesses, and anti-friction elements supported on the lower race members in a plane below the projecting portions of said lower race members and on which said upper race members are reciprocable.

2. The combination with a trough member of supporting means therefor comprising a body member to which the trough member is connected, said body member having guiding recesses substantially coextensive therewith and arranged along opposite portions thereof, track members having portions only thereof extended into said recesses, and anti-friction elements supported on said track members in a plane below the extended portions of said members and on which said body member is supported.

3. A ball frame for shaker chutes comprising channel-shaped track members, anti-friction elements in said track members, a body member supported for reciprocation on said anti-friction elements and provided with guiding recesses embracing portions of said track members whereby during reciprocation of said body mem-

ber excessive vertical and sidewise shifting thereof relative to the track members is prevented, and scraper members depending from said body member into the track members adapted during 5 reciprocation of the body member to clear the track members of foreign matter.

4. A ball frame for shaker chutes comprising channel-shaped track members, anti-friction elements in said track members, and a trough 10 supporting body member supported for reciprocation on said anti-friction elements and provided with guiding recesses embracing portions of said track members in such a manner that during reciprocation of said body member excessive vertical and sidewise shifting thereof relative to the track members is prevented.

5. A ball frame for shaker chutes comprising a base frame, spaced pairs of members secured to the base frame, the members of each pair being relatively so formed as to constitute a guideway, anti-friction elements supported for shifting movement in said guideways, and a trough 20 supporting body member supported for reciprocation on said anti-friction elements and having portions thereof lapping portions of the guideways in a plane above that at which the anti-friction elements are supported and in such a manner as to cooperate therewith to prevent excessive sidewise and vertical shifting of the body 25 member relative to the base frame.

6. In a ball frame for shaker chutes, a base frame comprising a pair of upwardly facing channel-shaped guideways having the web portions thereof horizontally arranged and the outer 30 leg of each of said guideways provided with an outwardly deflected extension, anti-friction elements in the guideways and a plate supported directly on said anti-friction elements and having opposite edge portions thereof formed to provide guiding recesses into which the before- 40 mentioned extensions project.

7. In a ball frame for shaker chutes including a base frame having guideways and anti-friction elements therein, a trough supporting body 45

member comprising a flat plate extended between said guideways and provided with flanged edge portions certain of which are arranged in the guideways and others of which are so formed and arranged relative to the guideways as to cooperate with the latter to restrain said body member against excessive sidewise and vertical shifting.

8. A trough supporting body member for shaker chute ball frames comprising a flat plate 80 having opposite edge portions thereof downwardly and inwardly flanged to provide guiding recesses, and angle shaped clips secured to the remaining edge portions of the plate and arranged adjacent said recesses.

9. In a ball frame for shaker chutes, a base frame including a pair of angle members having the legs thereof horizontally and vertically arranged respectively, upper portions of the vertical legs thereof being outwardly flanged, a trough 85 supporting plate, angle members secured to opposite portions of said plate and having portions of the horizontal legs thereof downwardly flanged to underlie the flanges of said first-named angles, the vertical legs of said second-named angles 90 being arranged substantially parallel with the vertical legs of the first-named angles to form therewith channel shaped guideways, and anti-friction elements arranged in said guideways and on which said second-named angles are 100 reciprocable.

10. A ball frame for shaker chutes comprising a supporting frame including spaced guideways, anti-friction elements supported in said guideways, and a plate reciprocably supported by said 110 anti-friction elements and having portions thereof formed to constitute guiding recesses so arranged as to receive portions of said guideways therein in a plane above that at which the anti-friction elements are supported whereby the 115 plate is restrained against excessive sidewise and vertical shifting during reciprocation.
